H. A. DREFFEIN

REGULATOR FOR GAS PRODUCERS

Filed June 1, 1920

Inventor
H.A. Dreffein
By: Sheridan & Sons, Sheridan and Smith, Atty.

UNITED STATES PATENT OFFICE.

HENRY A. DREFFEIN, OF CHICAGO, ILLINOIS.

REGULATOR FOR GAS PRODUCERS.

Application filed June 1, 1920. Serial No. 385,479.

To all whom it may concern:

Be it known that I, HENRY A. DREFFEIN, a citizen of the United States, residing at Chicago, in the county of Cook and State of Illinois, have invented certain new and useful Improvements in Regulators for Gas Producers, of which the following is a specification.

This invention relates to improvements in regulators for gas producers, and its purpose is to prevent accident and secure greater efficiency in the operation of devices of this kind.

As gas producers are now generally operated a mixture of air and steam, formed by an injector, is passed upwardly through the fuel bed in the gas producer, and the amount of gas produced, and the consequent pressure of the gas in the gas main and in the storage chamber, is controlled by regulating the flow of steam to the injector. For this purpose a gasometer, or equivalent device, is connected to the gas main and operated by the pressure of the gas therein to regulate the degree of opening of a valve in the steam pipe leading to the injector of the producer. It has been found in practice that air sometimes leaks into the gasometer, or the connected pipes, thus forming an explosive mixture therein, with the result that violent explosions sometimes occur and cause serious damage to the entire apparatus, as well as injury to those tending the operation thereof.

The principal object of this invention is to overcome the difficulty just pointed out by providing an improved regulator in which the formation of an explosive mixture in the gasometer or associated parts is prevented. A further object of the invention is to provide a liquid trap or seal in the connection between the gas main and the gasometer or regulating device. Another object is to provide improved means for automatically maintaining the liquid seal. A further feature of the invention is the provision of means for maintaining the liquid seal and preventing the presence of a combustible mixture in the gasometer by means of a mixture of air and steam drawn directly from the injector of the gas producer. Other objects relate to various features of construction and arrangement which will appear more fully hereinafter.

The nature of the invention will be understood from the following specification,

taken in connection with the accompanying drawing, in which one embodiment is illustrated.

The single sheet of drawings represents a somewhat diagrammatic view of a gas producer and the connected apparatus constituting the regulating system of the present invention, parts of the apparatus being illustrated in section, in order to show the construction thereof more clearly.

In the drawings, the invention is shown in connection with a gas producer 10, having a gas main 11 leading therefrom, and a funnel 12 for introducing fuel. The usual steam injector 13 is connected to the lower part of the gas producer for injecting a mixture of air and steam through the bed of fuel. This steam injector is adapted to draw air through the upper opening at 13^a thereof, and this air is intermingled with steam, which is discharged through the nozzle 13^b connected to the lower end of the steam pipe 14. The steam pipe 14 has a smaller tube 15 leading therefrom to a suitable pressure gauge, and it communicates with a pipe 16 having a controlling valve 17 connected therein for regulating the flow of steam. Hand operated valves 18 are connected in the pipe 16 on opposite sides of the regulating valve 17, and a by-pass pipe 19 is connected around the pipe 16 and valve 17, so that the steam flowing from a steam boiler through the supply pipe 20 may be caused to pass around the regulating valve 17 when desired. The by-pass 19 is normally closed by a regulating valve 21.

The regulating valve 17 is controlled by a valve stem 23, which is pivotally connected to an operating arm or lever 24. This lever is pivotally connected at one end to the pivoted link 25 mounted on the valve casing, and a weight 26 is slidably mounted on the lever 24 to regulate the opening and closing of the valve. The end of the lever 24, opposite the link 25, is flexibly connected to a pulley 28, and this pulley is adapted to be engaged by a flexible cord or rope 29, which is rigidly attached at 30 to a fixed support 31. The cord 29, after passing around the pulley 28, is carried around another pulley 32, which is also suspended from the fixed support 31, and the cord 29 then passes downwardly and is connected at the point 33 to the movable element 34 of a suitable gasometer, or other pressure-actuated device 35. This gasometer comprises the cup-

shaped member 34, which is inserted in an inverted position in the tank or vessel 36 containing water or other fluid 37. A pipe leads upwardly through the bottom of the vessel 36 and extends above the level of the liquid therein, so that the air or other gas discharged by the pipe 38 will enter the space 39 within the member 34 and above the level of the liquid in the tank. This 10 air or gas in the space 39 is adapted to expand in accordance with the pressure thereof, thereby causing the member 34 and the connecting flexible cord 29 to move in response to the pressure of the gas and permit 15 a corresponding movement of the lever 34 which operates the valve 17.

The vertical pipe 38 is connected to a horizontal pipe 40, which leads downwardly into the upper end of a fluid trap or seal 41. 20 The end of the pipe 40 is provided within the casing of the trap 41 with a divergent tip 42, which is adapted to extend below the surface of the water 43 contained within the trap. A pipe 44 leads to the trap 41 just 25 above the level of the liquid therein, and is connected to the gas main 11. A hand-operated valve 45 is connected in this pipe 44 and a U-shaped outlet or overflow 46 is also connected in this pipe between the valve 30 and the trap, in order to permit the discharge of the water which flows outwardly through the pipe 44 from the interior of the trap.

The pipe 50, having a steam cock 51 connected therein, communicates with the pipe 40 between the trap 41 and the pressure-controlled device 35. This pipe 50 has a valve 52 connected therein, and it leads through a pipe 53 to the steam injector 13, 40 so that a portion of the mixture of air and steam formed within the injector 13 is adapted to pass through the pipes 53 and 50 to the pipe 40. A valve 54 is connected to the end of the pipe 53, in order to permit 45 the discharge of the contents of this pipe when desired.

In the operation of the apparatus, the valves 18, 45, 51, 52, and 54, are maintained in open position, and the valve 21 is closed, 50 so that the flow of steam to the injector 13 is controlled only by the regulating valve 17, and the flow of steam and air through the pipe 50-53 is regulated only by the degree of opening of the valves 51 or 52. The mixture of air and steam which passes into the pipe 40 normally has a pressure slightly greater than the pressure of the gas in the main 11, so that it will bubble through the water in the trap 41 and pass into the pipe 44, where it mingles with the producer gas. The continual condensation of the steam contained in the mixture introduced into the pipe 40 will result in automatically maintaining the level of the water 43 in the trap 60 41, and the excess supply of water will pass

outwardly through the U-shaped outlet 46. When the pressure of the gas in the main 11 increases, the increased pressure will prevent the contents of the pipe 40 from bubbling through the water of the trap 41, with 70 the result that the continued flow of steam and air into the pipe 40 will increase the pressure of this mixture in the chamber 39 of the gasometer, so that the member 34 of the gasometer will rise and permit a lowering of the lever 24 in order to close, or partially close, the valve 17, and thereby decrease the flow of steam into the injector 13. This will result in a decrease in the production of gas by the gas producer, so that 80 the pressure of the producer gas in the main 11 will then decrease. When the pressure of the producer gas falls below the desired limit, the contents of the pipe 40 will again be permitted to bubble through the water 85 in the trap 41, thus reducing the pressure in the chamber 39 of the gasometer and permitting the valve 17 to open under the influence of the weight 26 on the operating lever 24. In this way the pressure of gas 90 within the main 11 is maintained substantially constant at a pressure which may be determined by adjusting the position of the weight 26.

It will be seen that this automatic regulation of the gas producer is effected without the necessity of employing any auxiliary fluid supply, since the mixture of air and steam is taken from the injector 13, where this mixture is constantly being formed by 95 a part of the gas-producing apparatus. Owing to the fact that only a mixture of air and steam is introduced into the chamber 39 of the gasometer, the formation of 100 an explosive mixture in the chamber of the gasometer is prevented, and at the same time the steam mixture has the advantage that it 105 automatically maintains the water trap 41 by which the flow of producer gas from the main 11 to the gasometer is prevented. 110

Although I have shown and described one embodiment of the invention, for purposes of illustration, it will be understood that it may be constructed in various other forms without departing from the spirit of the invention, as defined in the appended claims. 115

I claim:—

1. The combination with a gas producer of an injector for introducing a mixture of air and steam into said producer, a steam 120 pipe leading into said injector, means actuated in proportion to the pressure of the gas given off by said producer for regulating the flow of steam through said pipe, and means for positively preventing the flow of 125 producer gas into said regulating means.

2. The combination with a gas producer of an injector for introducing a mixture of air and steam into said producer, a steam pipe leading into said injector, a valve in 130

said steam pipe, a pressure-actuated device for operating said valve, means for conveying a mixture of air and steam from said injector to said pressure-actuated device, a conduit adapted to receive gas discharged by said producer, and means common to said conduit and said conveying means for positively preventing the flow of producer gas from said conduit into said pressure actuated device while permitting the flow of said mixture in the other direction.

3. The combination with a gas producer of an injector for introducing a mixture of air and steam into said producer, a steam pipe leading into said injector, a valve for controlling the flow of steam through said pipe, a gasometer operatively connected to said valve for regulating the opening and closing thereof, a conduit leading from said gasometer to the gas main of said producer, means for conveying a mixture of air and steam from said injector to said conduit, and means connected in said conduit for preventing the flow of producer gas in one direction and permitting the flow of said mixture in the other direction.

4. The combination with a gas producer of an injector for introducing a mixture of air and steam into said producer, a steam pipe leading into said injector, a valve for controlling the flow of steam through said pipe, a gasometer operatively connected to said valve to regulate the opening and closing thereof, a conduit leading from said gasometer to the gas main of said producer, a fluid trap connected in said conduit, and a pipe leading from said injector and communicating with said conduit between said trap and said gasometer for conveying a mixture of air and steam thereto.

5. The combination with a gas producer of an injector for introducing a mixture of air and steam into said producer, a steam pipe leading into said injector, a valve for controlling the flow of steam through said pipe, a gasometer operatively connected to said valve to regulate the opening and closing thereof, a conduit leading from said gasometer to the gas main of said producer, a fluid trap connected in said conduit, and a pipe leading from said injector and communicating with said conduit between said trap and said gasometer for conveying a mixture of air and steam thereto, said trap being adapted to permit the flow of said mixture therethrough when the pressure of said mixture is above the pressure of the producer gas and to prevent the flow of the producer gas therethrough when the pressure of said producer gas is above the pressure of said mixture.

6. The combination with a gas producer of an injector for introducing a mixture of air and steam into said producer, a steam pipe leading into said injector, a valve for controlling the flow of steam through said pipe, a gasometer operatively connected to said valve to regulate the opening and closing thereof, a conduit leading from said gasometer to the gas main of said producer, a fluid trap connected in said conduit, and a pipe leading from said injector and communicating with said conduit between said trap and said gasometer for conveying a mixture of air and steam thereto, said trap being adapted to permit the flow of said mixture therethrough when the pressure of said mixture is above the pressure of the producer gas and to prevent the flow of the producer gas therethrough when the pressure of said producer gas is above the pressure of said mixture, said trap being automatically maintained by the condensation of said steam.

7. The combination with a gas producer of an injector for introducing a mixture of air and steam into said producer, a steam pipe leading into said injector, a valve for controlling the flow of steam through said pipe, a gasometer operatively connected to said valve to regulate the opening and closing thereof, a conduit leading from said gasometer to the gas main of said producer, a fluid trap connected in said conduit, a pipe leading from said injector and communicating with said conduit between said trap and said gasometer for conveying a mixture of air and steam thereto, said trap being adapted to permit the flow of said mixture therethrough when the pressure of said mixture is above the pressure of the producer gas and to prevent the flow of producer gas therethrough when the pressure of said producer gas is above the pressure of said mixture, and means for permitting the overflow of water from said trap.

8. In combination with a producer, a gas main leading therefrom, a steam pipe leading thereto, a regulating valve associated with said steam pipe, a gasometer, means operatively interposed between said gasometer and said regulating valve, a fluid trap, a duct leading thereto from said gas main, a second duct leading thereto from said gasometer, and means to supply non-combustible fluid under pressure to said second duct, whereby the flow of gas from said main to said gasometer will be prevented.

In testimony whereof, I have subscribed my name.

HENRY A. DREFFEIN.
